COMBUSTION OF MIXED GASES.

1,223,248.

Specification of Letters Patent. Patented Apr. 17, 1917.

Application filed October 8, 1910, Serial No. 586,058. Renewed March 17, 1917. Serial No. 155,617.

To all whom it may concern:

Be it known that we, WILLIAM ARTHUR BONE, residing at the University, Leeds, in the county of York, professor of applied chemistry, JAMES WILLIAM WILSON, residing at Carlton Works, Armley, Leeds, in the said county, gas-stove manufacturer, and CYRIL DOUGLAS McCOURT, residing at 13 Malwood road, Balham Hill, London, S. W., 10 England, chemist, subjects of the King of Great Britain and Ireland, have made certain new and useful Inventions Relating to the Combustion of Mixed Gases, of which the following is a specification, taken in connection with the accompanying drawing, which forms part of the same.

Our invention relates to apparatus for burning a mixture of two or more gases or vapors which combine together to produce 20 heat, hereinafter called the "explosive mixture" (such for instance as a mixture of coal gas and air), the objects being to obtain complete combustion and also to utilize as much as possible of the heat for any desired 25 purpose. The purposes to which our apparatus may be applied are numerous and include gas fires of various kinds.

In the accompanying drawing showing in a somewhat diagrammatic way several illustrative embodiments of this invention, Figure 1 is a sectional view through one form of diaphragm apparatus and Fig. 2 is a similar view through a form of apparatus comprising a composite diaphragm.

30 In Fig. 1 of the accompanying drawing is represented a simple form of that which may be described as the fundamental unit of our apparatus, which consists essentially of a permeable diaphragm A of sufficiently refractory material in conjunction with a chamber or casing C. The porous diaphragm constitutes one wall of the chamber, into which explosive mixture is led through a pipe. The mixture passes through the diaphragm and is caused to ignite on the face 40 of exit E or in close proximity thereto. For instance an explosive mixture of coal gas and air in proper proportions and at various

pressures, examples of which are hereinafter given may be used for many household and 50 industrial purposes. The supply of gas and air in proper proportions may be suitably regulated by ordinary means, so that the combustion may take place in, upon, or close to the surface F of the porous diaphragm 55 A. The regulation of the supply of the mixture having been adjusted, the face E of the diaphragm A becomes hot or incandescent, and is maintained in a heated or incandescent state by the continued flow of the explosive 60 mixture through the porous diaphragm, and its combustion in, upon, or near the surface of same. The flow can be regulated so that little or no flame appears beyond the surface of the diaphragm while the 65 said surface is maintained in a state of glow or incandescence.

With regard to the combustible mixture the proportions of the combining gases will be substantially the proportions necessary 70 for complete combustion. In general with coal gas, we prefer to employ a little excess of air. For example in the case of a coal gas which theoretically requires about five and a half times its own volume of air for complete combustion, we have obtained good results with about seven times its own volume of air.

The joint between the diaphragm A and its seating S may be of white lead or an asbestos paste or other suitable luting material, and a ring R may be used to secure the porous diaphragm in position. The margin of the diaphragm may be glazed so as to prevent escape of gas through its edges. The diaphragm may be arranged in various ways depending on the object in view. In Fig. 2 similar means are shown for mounting a diaphragm which in this case is of composite character, the portion A' being of different 80 porosity from the layer A² forming the outer or working face of the diaphragm. In some cases more than one diaphragm may be employed. Where plane diaphragms are employed they may be placed horizontally, vertically or at my desired angle and the 85

heated external surface may be either the superior or inferior surface.

A porous diaphragm of this general character may of course be formed with working faces of any desired shape or contour. It should be noted however that where there is, with any particular mixture of gases a tendency to heat the diaphragm so much as to cause firing back, the arrangement must be such as to utilize or convey away the heat with sufficient rapidity to prevent such firing back.

For instance, in using water-gas there is always a tendency to fire back, but this may be in a large measure counteracted by employing diaphragms of a closer or less permeable texture so as to produce a steeper pressure gradient in the diaphragm, thereby increasing the velocity of flow of the explosive mixture through the diaphragm. Accordingly it is desirable in any given case to select from a series of diaphragms of different permeabilities that diaphragm which on trial is found to be sufficiently impervious to prevent firing back or back flashing under the given conditions. Also the tendency to fire back may be checked by mixing a larger proportion of inert gas or air with the explosive mixture. Further, where there is risk of firing back the progressive accumulation of heat in a confined space must be avoided. On the other hand when using poor gases as for example blast furnace gas, the production of the glow or incandescence depends on conserving a certain amount of the heat on the surface of the diaphragm.

It should be noted that in our apparatus although the products of combustion necessarily pass away in a heated condition and thus carry off some of the heat generated, the arrangement before described enables us when desired to reduce the convective heat outflow and to utilize a large proportion of the heat in radiant form by radiation from the surface of the heated diaphragm, which for some applications of our invention is a matter of importance.

The diaphragms or the like may be produced from various materials either separately or in combination, and may vary considerably in their nature, shape and construction, examples of which are hereinafter specified. But it must be understood that we do not confine ourselves solely to the said examples and that we may adopt other constructions in the nature of a diaphragm or the like, so long as same enables us to burn a mixture of gases or the like and produce in, upon, or close to the surface of the medium, a combustion with little or no flame.

In the production of the diaphragms suitable refractory materials are employed and

combined so as to give the desired degree of porosity and permeability.

Materials of a nature to burn out and leave pores or interstices may be combined with refractory materials, for example we have used mixtures of fire-clay with fine seed, bran and spongy plumbago produced by acting on Ceylon flake plumbago with strong fuming nitric acid and applying heat.

In some cases as shown in Fig. 2 we may combine two or more diaphragms of differing degrees of permeability or porosity such diaphragms being formed into one or superimposed, the more porous diaphragm being that which is on the side of exit of the gaseous mixture.

The degree of porosity will be determined by the quantity of organic material employed. In general we prefer to employ fine seed for this purpose as being a material the individual grains of which are substantially of the same size and shape. We find that rape seed is specially suitable for this purpose. The proportions will vary somewhat with the nature of the clay employed, some clays being by nature when burnt more porous than others, and in every case it is necessary to determine by trial the proper proportions for producing a desired degree of porosity. But the examples which we will give will serve to indicate in some measure the nature of the mixtures which are found suitable in practice.

In making diaphragms suitable for working with coal-gas and air at a pressure of six inches water gage, we mix 18 parts by weight of powdered Stourbridge fire-clay in the dry state with 8 parts by weight of English rape-seed, and mix therewith sufficient water to render the mixture suitable for molding. It will be found that the plasticity of the mixture becomes rapidly lost on standing owing to the drinking up of the water by the dry seed. Only sufficient of the mixture should be made to suit immediate requirements, and the diaphragms should be molded immediately after the mixture is made and before it has lost its plasticity. To obviate in part the loss of plasticity herein before mentioned the rape-seed may be steeped in water prior to mixing with the clay. The molded diaphragms are carefully dried, baked and burned in an oxidizing atmosphere so as to insure the complete burning out of the seed.

After burning, that surface of the diaphragm which is to form the heated surface is preferably roughened with a rasp, sand blast, or by any other known means. Or both surfaces of the diaphragm may be so roughened.

By employing the above mentioned proportions we have made diaphragms which when three quarters of an inch thick are able

at a pressure of six inches water gage to admit of a flow per square inch of heating surface of 6.4 c. ft. per hour of a gaseous mixture consisting of one volume of gas with 6 or 7 volumes of air.

5 By employing a mixture consisting of 18 parts by weight of dry powdered Stourbridge fire-clay with 12 parts by weight of English rape-seed we have made diaphragms which when three quarters of an inch thick admit of the same gaseous flow at a pressure of one inch water gage.

Another method of making porous diaphragms consists in consolidating a mass of granules or fragments of refractory material in such a manner as to leave pores or interstices throughout the mass. For example burnt fire-clay coarsely ground and preferably meshed to a uniform size mixed with 15 a powder adapted to act as a cementing material when highly heated may be disposed in the form of diaphragm required, and burned. Thus for working at a pressure of about one quarter of an inch water gage, 20 with a mixture of coal gas and air the grade of fragments employed is that which passes through a sieve of eight meshes to the linear inch but will not pass a sieve of sixteen meshes to the linear inch. These fragments 25 are wetted, mixed with one-tenth of their weight of finely ground feldspar and molded or disposed into the form of diaphragm required, slight pressure only being used to give the diaphragm the desired form or 30 configuration and burnt at a temperature of 35 1,300 or 1,400° C. A series of such diaphragms made with differing degrees of fineness can be used to determine which is the best grade to use for any particular gaseous 40 mixture.

What we claim as our invention is:

1. In apparatus for burning fuel, a porous composite diaphragm composed of porous non-metallic material and comprising a porous outer layer and a relatively denser inner portion, means to feed an explosive mixture of gaseous or vaporous fuel and of supporter of combustion therefor through said diaphragm, said diaphragm being adapted 45 when heated to cause the accelerated combustion of said explosive mixture to occur substantially without visible flame, within the porous outer layer of said diaphragm and maintain incandescence thereof, the incandescent surface of said diaphragm being 50 free to transmit by radiation heat supplied thereto from said combustion.

2. In apparatus for burning fuel, a thick porous composite refractory diaphragm comprising a porous outer layer and a relatively denser inner portion, means to feed an explosive mixture of gaseous fuel and of supporter of combustion therefor through said diaphragm, said diaphragm being adapted 55

when heated to cause the accelerated combustion of said explosive mixture to occur substantially without visible flame within said diaphragm and maintain incandescence thereof.

3. In apparatus for burning fuel, a porous composite refractory diaphragm consisting of non-metallic refractory material comprising a porous outer layer and a relatively denser inner portion, means to supply gaseous fuel and means to supply air and to 70 form an explosive mixture thereof and feed the same through said diaphragm, said diaphragm being adapted when heated to cause the accelerated combustion of said mixture to occur substantially without visible flame 75 within the outer layer of said diaphragm and maintain incandescence of the outer surface thereof.

4. In apparatus for burning fuel, a porous refractory diaphragm of non-metallic refractory material, a casing within which said diaphragm is mounted, means to render the edge portions of said diaphragm substantially impervious to gaseous material, and means to feed to said casing and through 80 said diaphragm an explosive gaseous mixture containing substantially the combining proportions of air and of gas having high calorific value, said diaphragm being adapted when heated to cause the accelerated combustion of said explosive mixture to occur 85 substantially without visible flame within the porous outer layer of said diaphragm and maintain incandescence thereof.

5. Apparatus for burning explosive gaseous mixtures, comprising a porous refractory diaphragm having a portion or layer adjacent its outer or outlet side which is more porous than the inner portion of the diaphragm, and means for maintaining a 100 supply of the explosive mixture against the inlet side of the diaphragm to cause the mixture to enter and move through the passages of the diaphragm to burn within the outer more porous layer thereof.

6. Apparatus for producing heat, comprising a porous refractory diaphragm having a portion or layer adjacent its outer or outlet side which is more porous than the inner portion of the diaphragm, a gas chamber one wall of which is formed by the inner denser side of the diaphragm, and means for mixing a fuel gas and air in proportions to form an explosive gaseous mixture and for supplying the explosive mixture thus formed to said chamber, whereby the mixture will be caused to enter and move through the passages of the diaphragm to burn within the outer more porous layer thereof.

7. Apparatus for producing heat, comprising a porous refractory diaphragm, a gas chamber one wall of which is formed by said diaphragm, and means for mixing a

fuel gas and air in proportions to form an explosive gaseous mixture and for supplying the explosive mixture thus formed to said chamber, whereby the mixture will be caused to enter and move through the passages of the diaphragm to burn adjacent its outer face, the passages of the diaphragm being of a size to prevent back-flashing of the explosive mixture.

In witness thereof, we have hereunto set **10** our hands, in the presence of two witnesses.
